CATALYTIC CRACKING

Clare Kenneth Viland, Martinez, Calif., assignor to Tide-water Oil Company, a corporation of Delaware

No Drawing. Application September 16, 1955
Serial No. 534,882

10 Claims. (Cl. 196—50)

This invention relates to the catalytic cracking of hydrocarbon oils which are normally low in non-basic nitrogen compounds. More particularly, it pertains to the catalytic cracking of hydrocarbon oils in the presence of controlled amounts of non-basic organic nitrogen compounds. It has for its primary object the improvement in yield and quality of products from the catalytic cracking of such oils. An important object is the improvement in antiknock properties of gasolines derived from such catalytic cracking.

It is now well recognized that the presence of organic nitrogen compounds in the feed stocks to catalytic cracking operations has a detrimental effect on the yields and product distribution. It has been generally found that gasoline yields can be improved and coke production reduced by lowering the nitrogen content of the feed stocks. Methods generally recommended for reducing the nitrogen content (such as dilute acid treating and the like) preferentially remove the more basic nitrogen compounds (pyridines, quinolines, etc.) with lesser or no effect on the non-basic nitrogen compounds present (pyrroles, indoles and carbazoles).

In accordance with the present invention it has been found that, contrary to the general conception concerning nitrogen compounds in catalytic cracking feed stocks, the presence of non-basic nitrogen compounds in the feed stock has a beneficial rather than a detrimental effect on the yield and, particularly, the anti-knock rating of the gasoline produced. The invention, therefore, broadly contemplates the enhancement of the catalytic cracking of stocks low in non-basic nitrogen content by the addition thereto of organic non-basic nitrogen compounds.

The non-basic organic nitrogen compounds preferred for this purpose are those having boiling points within the approximate boiling range of the charge stock. Since most catalytic cracking operations are conducted on stocks with boiling ranges above 400° F. and below about 1000° F., the nitrogen compound chosen should preferably have a boiling point above about 400° F. Indole, carbazole and their homologues have been identified as present in various nitrogen-containing gas oils, and these non-basic compounds are suitable for use in the invention. However, other high-boiling non-basic nitrogen compounds are suitable, such as, for example, quinoxaline, diphenylamine, phenazine, indazole and benzotriazole. Although the high-boiling non-basic nitrogen compounds are preferred, since they have the approximate volatility of the hydrocarbon charge stock, lower boiling non-basic nitrogen compounds such as pyrimidine, pyrazine, pyrrole, alkyl nitriles, and their homologues, for example, may be found suitable.

The catalytic cracking charge stocks which are adaptable for improvement in accordance with the invention are those naturally containing less than about 0.1 weight percent of non-basic nitrogen, although some improvement may be realized with stocks containing up to 0.3% of non-basic nitrogen. As stated above, basic nitrogen compounds are detrimental to catalytic cracking opera-

2

tions. Consequently, basic nitrogen compounds should be removed as far as practical. Various methods are known in the art for the removal of basic nitrogen compounds, any one of which may be used, if needed, in conjunction with the present invention. Satisfactory results are generally obtained by extraction with dilute sulfuric acid such as 25% H_2SO_4 for example. The removal of the basic nitrogen compounds may be effected either before the addition of the non-basic nitrogen compounds, or after the addition and before the catalytic cracking operation.

The amount of non-basic organic nitrogen compound to be added to the catalytic cracking charge stock in accordance with the invention preferably should be sufficient to result in a total non-basic nitrogen content in the charge stock of about 0.3%. However, substantial results may be obtained where the amount of added non-basic nitrogen is 0.1%. Where the total non-basic nitrogen content of the charge is increased above about 0.4% some gain in antiknock value of the cracked gasoline may be realized, but usually at the expense of lower yields. In some instances this may be desirable.

The non-basic nitrogen compounds may be added to the catalytic cracking charge stock at any time prior to the actual cracking operation. For example, if readily soluble, it may be added to the charge stock while in storage, with whatever agitation is required for uniform dispersion. Alternately, a concentrate of the non-basic nitrogen compound may be made in a portion of the charge stock (which need not necessarily be identical to the remaining charge stock) or other suitable solvent, with the use of heat or whatever other aids are necessary to effect solution, and the concentrate blended into the catalytic charge stock in required proportions.

In accordance with a specific embodiment of the invention, the non-basic nitrogen content of a catalytic cracking charge stock low in nitrogen content is increased to the desired amount of between 0.1% and 0.5% by blending therewith a sufficient amount of a suitable hydrocarbon fraction naturally containing high amounts of non-basic nitrogen. Since the said fraction would normally also contain large amounts of basic nitrogen compounds, it should first be treated (such as, for example, by extraction with 25% sulfuric acid to remove the non-basic nitrogen compounds. Alternately, the blend of the low-nitrogen stock with the high-nitrogen fraction may be treated to remove the basic nitrogen compounds. As an example of catalytic cracking charge stock prepared in this manner, 60% by volume of a Minas (Sumatra) heavy gas oil having a boiling range of 500° to 1050° F., a non-basic nitrogen content of 0.04% and a basic nitrogen content of 0.025% is blended with 40% by volume of a deasphalted residuum representing 27% of Wilmington Crude oil, said residuum having a non-basic nitrogen content of 0.70% and a basic nitrogen content of 0.30%. The resulting blend, having a non-basic nitrogen content of 0.31% and a basic nitrogen content of 0.13%, after reduction of the basic nitrogen content to below 0.05% (by extraction with 25% H_2SO_4) is an excellent charge stock for catalytic cracking capable of giving yields and octant numbers superior to that obtained from either stock alone.

The invention may further be illustrated by the following example comprising experimental runs in a catalytic pilot plant of the type described in "Petroleum Processing," volume 6, No. 12, December 1951, pages 1370-1373. This pilot plant has proven to be capable of accurate control and to correlate closely with the operations of a 30,000 barrel per day commercial "fluid" catalytic cracking plant.

Four cracking runs in the pilot plant, at separate levels of conversion, were made on each of five charging stocks

using for each run a separate portion of equilibrium catalyst withdrawn from a commercial fluid catalytic cracking unit. The catalyst consisted of 21% synthetic silica-alumina microspheres and 79% natural catalyst of the sulfur resistant type manufactured from halloysite.

bon lay-down is the critical parameter for comparison.) The accompanying table shows the properties and results obtained (interpolated to a uniform carbon lay-down of 5% by weight of the charge) from each of the 5 five stocks described above.

TABLE
Effect on catalytic cracking yields of adding basic and non-basic nitrogen

Charging Stock	Low Nitrogen Content	Basic Nitrogen		Non-Basic Nitrogen	
	A	B	C	D	E
Properties of Oil:					
Basic Nitrogen, Wt. percent	0.02	0.30	0.58	0.02	0.02
Non-Basic Nitrogen, Wt. percent	0.04	0.04	0.04	0.37	0.65

It had a U. O. P. activity of 21 at the start of each pilot run.

The five charging stocks were prepared as follows:

(A) A 500° to 1050° F. gas oil was distilled from Minas (Sumatra) crude oil.

(B) 29 parts by weight of the basic nitrogen compound, isoquinoline, were dissolved in 971 parts of the Minas gas oil as prepared in (A), to obtain a stock containing about 0.3% of basic nitrogen but low in non-basic nitrogen.

(C) 59 parts by weight of isoquinoline were dissolved in 943 parts of the Minas gas oil to obtain a stock containing about 0.6% basic nitrogen but low in non-basic nitrogen.

(D) 27 parts by weight of the non-basic nitrogen compound, indole, were dissolved in 973 parts of the Minas gas oil to obtain a stock containing about 0.3% non-basic nitrogen but low in basic nitrogen.

(E) 52 parts by weight of indole were dissolved in 948 parts of the Minas gas oil to obtain a stock containing about 0.6% non-basic nitrogen but low in basic nitrogen.

All twenty cracking runs were conducted at the same temperature, 985° F., with the conversion level for the four runs on each stock being varied by controlling the charging rate, thereby varying the space velocity. From each set of four runs, the results obtainable for a uniform carbon lay-down on the catalyst were calculated for each stock. (Since carbon-burning capacity is the limiting factor of most commercial catalytic cracking units, the car-

The data summarized in the table show that when basic nitrogen is present in a catalytic cracking charge stock there is a marked detrimental effect on product distribution and on octane rating of the gasoline. The ratio of volume percent gasoline yield to weight percent of the charge burned as carbon in regenerating the catalyst decreases substantially when basic nitrogen is present. There is also a sharp drop in both the clear and leaded research octane ratings of the gasoline product. Likewise, there is a definite drop in the volatility of the debutanized gasoline when basic nitrogen is present. As stated prior, the art is generally aware of the detrimental effect of nitrogen compounds on catalytic cracking and their removal has been recommended. The data demonstrate 55 that the detrimental effects recognized by the art are due principally to basic nitrogen compounds.

However, the data also show that, in contrast to the detrimental effect which basic nitrogen has upon catalytic cracking, the presence of added non-basic nitrogen improves the antiknock quality of the cracked gasoline. Also, when present in amount of about 0.3% the non-basic nitrogen in the charge stock improves the volatility and yield of the gasoline.

As used herein, the term "catalytic cracking" is used in 70 the sense generally used by the art to denote the conversion of relatively heavy hydrocarbon fractions into relatively lighter products by vapor phase contact with silica, alumina, silica-alumina, silica-magnesia and the like catalysts at temperatures in excess of about 800° F. 75 Although operations with the well known "fluidized" bed

of catalyst are preferred, fixed bed and other types of moving bed are contemplated as equivalent for the purposes of the invention.

It is recognized that the various organic nitrogen compounds may differ in basicity throughout the range from strongly basic (such as pyridine) to definitely non-basic (such as carbazole). For the purposes of the invention, an organic nitrogen compound may be considered non-basic if it cannot be extracted from solution in hydrocarbons by a dilute solution of a strong mineral acid (such as 25% aqueous solution of H_2SO_4 , for example). Where used herein, the term "non-basic nitrogen" is used to denote the nitrogen contained in a non-basic organic nitrogen compound. Similarly, "basic nitrogen" is used to denote the nitrogen contained in the functional groups of a basic organic compound.

I claim:

1. In a process of catalytic cracking hydrocarbon oil wherein a hydrocarbon distillate having a boiling range between about 400° F., and 1050° F. and a non-basic nitrogen content not over about 0.1% by weight, is subjected to cracking in the presence of an active cracking catalyst to produce substantial amounts of gasoline components, the improvement which comprises adding to said distillate, prior to contact with said catalyst, a sufficient quantity of non-basic organic nitrogen compound to increase by at least 0.1% the non-basic nitrogen content of the distillate.

2. The process of claim 1 wherein the addition of the non-basic nitrogen compound to the distillate is accomplished by blending with said distillate an asphalt-free hydrocarbon fraction containing more than 0.6% non-basic nitrogen and less than 0.1% basic nitrogen.

3. The process of claim 1 wherein the non-basic nitrogen compound added is selected from the group consisting of benzotriazole, pyrimidine, indazole, phenazine, diphenylamine, quinoxaline, pyrazine, pyrrole, indole, alkyl nitriles, carbazole, and their non-basic homologues.

4. The process of claim 3 wherein the non-basic nitrogen compound has a boiling point above about 400° F.

5. The process of claim 4 wherein the non-basic nitrogen compound is indole.

6. The process of claim 4 wherein the non-basic nitrogen compound is carbazole.

7. The process of claim 1 wherein the total non-basic nitrogen content of the distillate after the addition of the non-basic nitrogen compound is between 0.2% and 0.4%.

8. The method of claim 1 wherein, as an additional step, a substantial amount of the basic nitrogen content normally present in the distillate is removed before contact with the catalyst.

10. 9. An improved method for cracking hydrocarbon oils which comprises blending a substantially asphalt-free hydrocarbon fraction containing less than 0.1% non-basic nitrogen with a substantially asphalt-free hydrocarbon fraction containing more than 0.6% non-basic nitrogen in proportions sufficient that the resulting blend contains between 0.2% and 0.4% non-basic nitrogen, then contacting the resulting blend with an active cracking catalyst under conditions of time and temperature sufficient to convert a substantial proportion of said blend into gasoline line components.

10. In the cracking of hydrocarbon oils, the combination of steps which comprises: contacting a substantially asphalt-free hydrocarbon fraction containing more than about 0.6% non-basic nitrogen and a detrimental amount

25 of basic nitrogen with an aqueous solution of a strong acid under conditions to extract from said fraction a substantial amount of the basic nitrogen content, removing the resulting acid phase, blending the resulting hydrocarbon fraction with a substantially asphalt-free hydro-

30 carbon fraction containing less than about 0.1% non-basic nitrogen in proportions that the resulting blend contains between about 0.2% and 0.4% non-basic nitrogen, and then contacting the resulting blend with an active cracking catalyst under conditions of time and temperature

35 sufficient to convert a substantial proportion of said blend into gasoline components.
